UNITED STATES PATENT OFFICE.

THOMAS A. MIGHILL, OF CAMBRIDGE, MASSACHUSETTS.

APPARATUS FOR PICKING UP PEAT-BLOCKS.

1,102,781.

Specification of Letters Patent.

Patented July 7, 1914.

Application filed April 20, 1911. Serial No. 622,256.

To all whom it may concern:

Be it known that I, THOMAS A. MIGHILL, a citizen of the United States, residing at Cambridge, in the county of Middlesex and 5 State of Massachusetts, have invented an Improvement in Apparatus for Picking Up Peat-Blocks, of which the following is a specification.

In the system for drying peat forming 10 the subject matter of my application for Letters Patent, Serial No. 617,060, filed March 27, 1911, a level-surfaced bed of finely divided dry peat is employed as a drying-bed on which the wet peat reposes 15 while drying. The wet peat is arranged on said bed in the form of blocks of suitable size, for fuel, and may be delivered thereto and the blocks formed by a machine such as shown in my application Serial No. 617,061, 20 and these blocks when partially dry may be turned over, if desired, and the drying operation permitted to continue until completed when the blocks are picked up and transported from the bed. This system is 25 economical and possesses many advantages.

This invention relates to an apparatus for picking up the dried blocks of peat and transporting them from the field to the place where the peat-blocks are to be stored.

30 In accordance with this invention the apparatus is portable and adapted to be propelled over the drying-field and is provided with means to automatically pick up the dried blocks of peat rapidly and convey 35 them to a suitable receptacle arranged on or connected with the apparatus.

The apparatus is adapted to be propelled and operated by power, so that it may be moved over a field of large area in a short 40 period of time and pick up the blocks.

As the capacity of the apparatus to pick up blocks and convey them to the receptacle is very large, and the apparatus, as an entirety, quite ponderous and heavy, said receptacle is arranged on an independent truck-frame or car, and means provided to detachably connect said car with the truck-frame or car bearing the picking-up and block-conveying-means, so that when the receptacle is filled the car bearing it may be detached from the car bearing the picking-up and conveying means and moved by its own power-operated propelling-means at a good speed, preferably much faster than the speed at which the apparatus is usually

driven, to a place where the peat-blocks are stored. The car bearing the receptacle is then returned and connected to the rear of the car bearing the picking-up and conveying-means, and the apparatus is then advanced and the operation continued. Two or more cars bearing receptacles for the dried peat-blocks, may be employed, particularly in case of emergency, so that the picking-up and conveying-means will not remain 60 idle during the harvesting time but for very short periods of time.

In the embodiment of my invention here shown, for the sake of illustration, the apparatus is adapted to be operated in connection with a drying-bed composed of finely divided dry peat, prepared between a pair of rails on which the apparatus is propelled, which forms a part of my newly devised system, but its essential principles 70 of operation are not confined to use in connection with such a bed.

The invention also comprehends essentially a set of inclined block-lifting fingers arranged horizontally and adapted to be 80 held in a fixed position and so supported that when moved forward their lower forward ends will pass beneath the blocks successively and lift them from the bed, and the succeeding blocks will push the blocks 85 ahead of them up and along said inclined fingers to the block-conveying means.

The invention also comprehends inclined block-conveying means here shown as comprising at least two inclined conveyers, arranged one in continuation of the other, which extend from the block-lifting fingers to a point above the top of the receptacle. The uppermost conveyor is made quite long and extends the greater part of the distance 90 between the block-lifting fingers and the receptacle, is held by fixed supports and is heavily constructed to adapt it to carry a heavy load, and the lowermost conveyor is made quite short compared with the afore- 100 said conveyor and is held by adjustable supports, so that it may be moved to cause its lower end to occupy different elevated positions, and the block-lifting fingers are supported at the lower end of said last named 105 conveyor so as to be raised and lowered with it and held in different positions of adjustment. When moving the apparatus to and from the field, said conveyor and block-lifting fingers will be raised into their out- 110

of-use position, so as not to engage any obstacles in the path of progress of the apparatus, but when moving the apparatus over the field for the purpose of picking-up the blocks said conveyer and fingers are lowered far enough to enable the lower forward ends of the fingers to pass beneath the blocks.

While each car bearing a coöperative part of the organized apparatus, may be equipped with an electric or other motor, and a controller therefor, yet, ordinarily, the motor on the car bearing the receptacle will be used to propel the entire apparatus by pushing along the car ahead of it.

15. The block-conveying means may be operated by the motor which is employed to operate the propelling-means for the apparatus, and in case only one motor is employed, said conveying-means will be operatively connected with said motor, but independent control of the conveying-means is very desirable. By employing an electric motor and controller therefor, the speed may be varied so that the apparatus may be advanced at a slow rate of speed when picking up the blocks and the car bearing the receptacle, when detached from the car bearing the picking-up and conveying-means, may be propelled at a high rate of speed to 25 the place of storage and to return.

30. Figure 1 is a side elevation of a portable apparatus embodying this invention for picking up peat-blocks and transporting them from the field. Fig. 2 is a plan view 35 of the apparatus shown in Fig. 1. Fig. 3 is an enlarged detail showing in front elevation a portion of a propelling-means for the apparatus. Fig. 4 is a plan detail of the parts shown in Fig. 3. Fig. 5 is an enlarged detail of a portion of the primary conveyer and picking-up device. Fig. 6 is a side elevation of a modified form of apparatus embodying my invention.

40. 10 represents the platform of the front car and 12 the platform of the rear car. Said platforms are constructed in any suitable manner and are respectively mounted on axles 13 bearing wheels 14, here shown as flanged, thus adapting them to run on 45 rails 15 between which a prepared bed 16 of dry peat is arranged. The blocks 17 to be picked up and transported from the field repose on the drying-bed and ordinarily will cover the entire area of said 50 bed, and as the drying-bed here shown is arranged between a pair of rails, and hence is quite long and narrow, the blocks are arranged in a correspondingly low, narrow row, the sides of which are arranged near 55 the rails.

60. On the front car and in advance of the means employed to pick up the blocks means are provided to engage the side blocks of the row and push them inward toward the middle. This is particularly desirable in

case the blocks are arranged on the bed quite close to the rails. Said means to push inward the side blocks of the row, as here shown, comprises a pair of horizontally arranged shoes 20, one at each side of the 70 apparatus, having their adjacent or inner sides or faces inclined in a direction from front to rear, as at 21, the opposite sides or faces being arranged in parallel with the rails. Said shoes are attached to the lower 75 ends of upright bars 22, 22, supported and guided to move vertically at the front end of the platform. Each bar may have a vertical slot 23, see dotted lines Fig. 1, to receive the attaching-bolts 24, to thus admit 80 of vertical adjustment when attached to the platform. Each bar has attached to its rear side, along its upper end portion, a rack-bar 25, which is engaged by a pinion 26, and both pinions 26, 26, are secured to a 85 horizontal shaft 27, supported in bearings on the platform, and having fixed to it a hand-wheel 28, or other means to turn it to revolve the pinions, and thus move the rack-bars, uprights and shoes up and down or 90 into and out of position to engage the blocks. Backward rotation of the shaft 27 is prevented by a ratchet-wheel 29, which is secured thereto and which is engaged by a pawl 30 on the frame.

95. When the apparatus is being moved to and from the field and at other desirable times the shoes may be raised into out-of-use position and subsequently lowered and held at any desired elevation. Said shoes 100 are thus stationarily held in position to engage the side blocks of the row and will be caused to operate and push inward toward the middle said side blocks by the advancing movement of the apparatus. While the 105 means thus described satisfactorily operates to push in toward the middle the side blocks of the row, and may be conveniently adjusted, yet my invention includes within its scope other means capable of pushing in 110 toward the middle the side blocks of a row when adapted to operate on the principle herein described. In rear of said pushing-in devices the means to pick up the blocks is arranged. As here shown, said means 115 comprises a set of horizontally arranged inclined fingers 35 attached at their upper ends to a supporting-bar 36, their lower forward ends being free. Said fingers are held stationary when in use with their lower 120 forward ends just below the bottoms of the blocks 17, so that as the machine is advanced said lower forward ends are caused to project beneath the blocks and to cause the succeeding blocks to push the blocks 125 ahead of them up and along the fingers, the blocks thus sliding along on the fingers in a direction toward the conveying means.

When using the apparatus in connection with a drying-bed such as shown in my ap- 130

lication No. 617,060; said fingers are of particular advantage for the reason that their lower forward ends will penetrate the top surface of the bed and thus easily project beneath the bottoms of the blocks. My invention, however, includes other forms of block-lifting means by which the blocks are picked up from the bed and caused to move rearwardly, which are adapted to operate on the principle of the block-lifting means here shown. In rear of said picking-up means, means are arranged to convey the blocks rearward to a receptacle, and, as here shown, said means comprehends the employment of two inclined endless conveyers arranged one in rear of and in continuation of the other.

The forward conveyer comprises an endless supporting-element and a bed supported by it. Said supporting-element, as here shown, comprises a plurality of endless sprocket-chains 40, arranged in parallel, and at a suitable inclination, their lower ends passing over sprocket-wheels 41, mounted on a shaft 42, and their upper ends passing over sprocket-wheels 43 fixed to a shaft 44. Said bed, as here shown, comprises a plurality of cross-slats or bars 45 attached to said inclined chains, and arranged at short distances apart. Said conveyer receives upon it the blocks from the inclined fingers, and conveys them in a rearward and upward direction to the next conveyer. The shafts 42 and 44 have their bearings in the side bars 46 of a frame of which the supporting-bar 36 for the fingers 35 forms a part, it being the lower end bar of said frame. Several rollers 47 are arranged in parallel between and journaled at their ends in said side bars 46, being located at suitable distances apart, and said rollers are arranged between the upper and under portions of the inclined endless conveyer, so that the upper portion of said conveyer may bear upon them and be supported by them to enable said conveyer to sustain a heavy load.

The shaft 44 is extended through and beyond the side bars 46, and its ends are journaled in the side bars of the platform 10, so that the frame bearing the endless conveyer and the block-lifting fingers is pivotally supported at its upper end by said shaft, and is adapted to be raised and lowered about said shaft as an axis for the purpose of moving the end of the conveyer and fingers into and out of operative position. This provision is desirable to enable the apparatus when being moved to and from the field to pass over obstacles. Stationary side boards 48 are arranged at each side of the moving conveyer to prevent the blocks from falling off, said boards being attached to the side bars 46 of the frame. For the purpose of raising and lowering said conveyer and fingers borne by it, and for holding them in different positions of

adjustment, a pair of links 50 are loosely connected at their lower ends by pins 51 to the side bars 46 of the frame, near its forward end, and the upper ends of said links are connected by pins 52 to the sides of toothed gears 53, secured to a horizontal shaft 54 having its bearing on the platform 10. Said wheels are engaged by pinions 55 secured to a horizontal shaft 56 also having its bearings on the platform 10, and a worm-wheel 57 is secured to said shaft 56, which is engaged by a worm 58, on the end of a shaft 59, which is extended rearward and is suitably supported on the platform 10, and has at its rear end a hand-wheel for turning it. Said hand-wheel is located within convenient reach of the operator, who by turning it may raise and lower the conveyer and fingers borne by it at will. As said conveyer is designed to be raised and lowered it is made quite short, and of little weight, so that it can be conveniently adjusted by hand. As said conveyer first receives the blocks from the picking-up device it is herein termed the primary conveyer. Said primary conveyer is designed to be positively driven to convey the blocks from the fingers in a rearward and upward direction to another endless conveyer arranged in rear thereof and in continuation thereof, and which is herein termed the secondary conveyer.

The secondary conveyer is stationarily supported and is designed to receive the blocks from the primary conveyer and convey them to a receptacle on the rear car. Said secondary conveyer comprises a plurality of sprocket-chains 60, arranged in parallel, their lower forward ends passing around sprocket-wheels 61, secured to a shaft 62, and their upper ends passing around sprocket-wheels 63, secured to a shaft 64, both of said shafts having their bearings in supports on the front platform 10, and a plurality of cross-bars 65 attached to said chains which are equidistantly spaced apart, see Fig. 2. Between the upper and lower inclined portions of said chains and extending from the shaft 64 to the shaft 62 an inclined surfaced table 66 is stationarily supported, which forms a bed for the blocks and on which the blocks are moved along by the moving cross-bars 65, which engage them. Said bed may be composed of numerous smooth boards extended lengthwise, see Fig. 2, and preferably arranged with narrow spaces between them to permit the passage or sifting through the bed of any loose pieces of dry peat which may become detached from the blocks. In case a drying bed of dried peat is employed, the pieces of dry peat which sift through said spaces will serve to re-surface the bed to compensate for the loss due to the pieces which cling to the blocks and are removed by them. But

few cross-bars 65 are ordinarily required as they act to only push along the blocks which are supported on the bed.

The blocks pass from the primary conveyer to and are delivered upon the lower end of the secondary conveyer and by said conveyer are moved rearward and upward, as shown in Fig. 1. Said secondary conveyer is designed to be positively driven, but preferably at a slower speed than the primary conveyer yet at a faster speed than the speed of the car. To drive said secondary conveyer and also the primary conveyer, as here shown, a drive-chain 70 passes around a sprocket-wheel 71 on a horizontal shaft 72, having its bearings at the rear end of the front platform 10, and also around a sprocket-wheel 73, secured to the shaft 64, at the upper end of the secondary conveyer, and a sprocket-wheel 75 is secured to a shaft 62 at the lower end of said secondary conveyer around which passes a drive-chain 76, which passes around a sprocket-wheel 77 secured to the shaft 44 at the upper end of the primary conveyer. Thus, as the shaft 72 is rotated both conveyers are moved. The sprocket-wheel 77 is of less diameter than the sprocket-wheel 75, hence the primary conveyer will be moved at a speed faster than the secondary conveyer.

The shaft 72 is designed to be driven by a motor on the rear car and as here shown it has secured to it a toothed gear 80, which is designed to be engaged by a toothed gear 81, secured to a horizontal shaft 82, having its bearings on the rear platform 12, and at the front end thereof, said gears being so disposed with respect to each other that when the two platforms approach and abut together, as shown in Fig. 1, said gears will mesh, yet disengagement thereof is permitted when the two cars are separated. The shaft 82 also has secured to it a sprocket-wheel 85, around which passes a drive-chain 86, which passes around a sprocket-wheel 87, sleeved upon a shaft 88, to which shaft a motor 89 is directly connected said motor being here shown as an electric-motor of any suitable construction having any usual or suitable controlled by which its operation and speed may be controlled and a clutch 90 is provided to connect the sleeve bearing the sprocket-wheel 87, with said shaft 88, and when connection is made said motor 89 will operate to drive the two conveyers.

The clutch 90 may be operated by a clutch-lever 91. Said motor 89 is also employed to propel the entire apparatus, and for this purpose a drive-wheel 96 is sleeved on the motor-shaft 88, around which a drive-belt 97 passes, which passes around a wheel 98 secured to one of the axles 13, and a clutch 99 is provided for connecting said

wheel 96, with said shaft 88, having a lever 65 100 to operate it.

Independent clutch-levers are employed to connect the motor-shaft with the axle and with the drive-shaft of the endless conveyers, so that the conveyers may be operated independently of the movement of the car as may be required when the car arrives at the end of a row, or the receptacle has been substantially filled, and it is proposed to detach it from the front car, in order that the blocks on the conveyers may be conveyed to the receptacle while the car is at rest. Moreover, said independent clutches permit the connecting of the motor with the axle to propel the car without operating the conveyers.

The platform of the rear car is arranged to support a large receptacle 102, for the blocks, and one end of the receptacle extends under the overhanging end of the secondary conveyer, as shown in Fig. 1, so that the blocks from said secondary conveyer will fall directly into the receptacle. Said receptacle has hingedly connected lids 103 at the bottom to close a large opening thereat, and said lids are designed to be operated by means here shown, consisting of links 105, connected to the opposite sides of the lids, which extend up and along the sides of the receptacle and are connected at their upper ends to crank-pins 106, arranged on the sides of a pair of toothed gears 107, 107, which are in engagement with each other, and one of said gears is engaged by a pinion 108 secured to a shaft 109, bearing a hand-wheel 110 for turning it, and a ratchet-wheel 112 is secured to said shaft which is engaged by a pawl 113 to prevent backward rotation thereof. This means for operating the lids is efficient, but my invention includes other means to operate them, which is constructed and arranged to operate on the same principle.

As illustrated in Figs. 1 and 2, a single motor is employed for the entire apparatus, which is arranged to propel the entire apparatus or the rear car separately when detached from the front car, and also to operate the conveyers when the two cars are connected or abutted together, so that a person standing on the platform 120 may control the operation of the motor and of the apparatus. When the cars are abutted together they may be held by a locking-device, which, as here shown, consists of a hooked lever 125, pivoted at 126, on the front platform and engaging a pin 127 on the rear platform, and a hand-lever 128 is connected with said lever 125 to operate it.

Referring to Fig. 6, the two cars are adapted to be coupled together by an ordinary link and pin and a separate propelling motor is provided on each car, the motor

140 on the rear car being arranged to propel said car, or it may be the entire apparatus and the motor 145 on the front car being arranged to propel the front car or the entire apparatus, or to assist the motor on the rear car in propelling the entire apparatus. And another motor 150 is arranged on the front car to operate the conveyers, it having a bevel-gear 151 on its shaft, which is engaged by a bevel-gear 152 on a shaft 153, which extends rearward and upward and has at its rear end a bevel-gear 154, which engages a bevel-gear 155 on the shaft 64, bearing the sprocket-wheels at the upper end of the secondary conveyer. In other respects the car shown in Fig. 6 is substantially the same as shown in Fig. 1.

I claim:

1. In an apparatus for picking up peat blocks and transporting them, a power car for the transportation of the blocks, a conveyer car, pick-up mechanism carried by said conveyer car, a power-driven element on the power car, an actuating element on the conveyer car and operatively connected to the pick-up mechanism, and means for guiding both cars in movement to automatically connect the power-driven element and actuating element when the cars are in predetermined arrangement.
2. In an apparatus for picking up peat

blocks and transporting them, a power car for the transportation of the blocks, a conveyer car, pick-up mechanism carried by said conveyer car, a power-driven gear on the power car, an actuating gear on the conveyer car and operatively connected to the pick-up mechanism, and tracks for guiding both cars in movement to automatically connect said gears when the cars are in predetermined arrangement.

3. In an apparatus for picking up peat blocks and transporting them, a power car for the transportation of the blocks, a conveyer car, pick-up mechanism carried by said conveyer car, a power-driven gear on the power car, an actuating gear on the conveyer car and operatively connected to the pick-up mechanism, tracks for guiding both cars in movement to automatically connect said gears when the cars are in predetermined arrangement, and a means for connecting the respective cars to maintain them in such predetermined arrangement.

In testimony whereof, I have signed my name to this specification, in the presence of two subscribing witnesses.

THOMAS A. MIGHILL.
